SPRING PLANK

Rudolph Leppla, Pittsburgh, Pa., assignor to
McConway & Torley Corporation, Pittsburgh,
Pa., a corporation of Pennsylvania

Application April 3, 1946, Serial No. 659,356

4 Claims. (Cl. 105—190)

1

This invention relates to railway car trucks, and more particularly to spring planks of the type that are suspended from a transom by means of links pivoted to swing transversely of the truck and that are provided with seats for supporting groups of coil springs which yieldably support the truck bolster.

The invention has for an object to provide a spring plank of the character referred to that is in the form of a one piece metal casting provided with spring seats and integral flanges and lugs for positioning the bolster supporting springs.

It is also an object of the invention to provide a one piece spring plank having integral pivot engaging bearings beneath the spring seats.

A further object of the invention is to provide a one piece spring plank having integral stiffening flanges intermediate the ends thereof that are adapted to serve as supports for a brake beam supporting bracket.

It is also an object of the invention to provide a one piece cast metal spring plank provided with integral spring seating end portions provided with positioning lugs on their upper faces and pivot engaging bearings on their under faces, the planks being of relatively light weight and of a configuration such that uniform cooling of the casting is provided and distortion of the casting and weakening thereof due to internal strains is avoided.

With the above and other objects in view, the invention may be said to comprise the spring plank as illustrated in the accompanying drawings, hereinafter described and particularly set forth in the appended claims, together with such variations and modifications thereof as will be apparent to one skilled in the art to which the invention pertains.

Reference should be had to the accompanying drawings forming a part of this specification, in which:

Figure 1 is a fragmentary transverse vertical section through a truck side frame showing the transom, spring plank and bolster in side elevation;

Fig. 2 is a section taken on the line indicated at 2—2 in Fig. 1;

Fig. 3 is a top plan view of the spring plank;

Fig. 4 is a longitudinal section through the spring plank taken on the line indicated at 4—4 in Fig. 3;

Fig. 5 is a transverse vertical section on an enlarged scale through the spring seating portion of the bolster, the section being taken on the line indicated at 5—5 in Fig. 4, and

2

Fig. 6 is a section taken on the line indicated at 6—6 in Fig. 3.

In the accompanying drawings the invention is shown applied to a railway car truck of a conventional design which includes a transom 1 that is supported at its ends by coil springs 2 mounted in side frames 3, it being understood that the end of the transom opposite that shown in the drawings is supported in an identical manner upon the side frame at the opposite side of the truck. The transom 1 has bearings 4 that support pivots 5 of links 6 which have longitudinal slots 7 adjacent their lower ends to receive the ends of pivot bars 8 which support a spring plank 9. As shown in Fig. 3, the spring plank 9 has widened end portions 10 forming seats for groups of coil springs 11 which support a bolster 12, a safety hanger 13 attached to the transom 1 serving to support the spring plank in case of failure of the supporting links or pivots.

The spring plank 9 has a marginal flange 14 that extends entirely around the sides and ends of the plank, the flange 14 having rounded shoulder portions 15 at the inner corners of the spring seats 10 and rounded portions 16 at the outer corners of the spring seats, the rounded portions 15 and 16 of the flange conforming to the peripheries of the coil springs 11 and serving to position the lower ends thereof on the seats 10. The narrow portions of the spring plank intermediate the widened portions 10 are stiffened by integral, laterally projecting flanges 17 and vertical bracing webs 18 integral with the flanges 17 and 14. The stiffening flanges 17 also provide means for attachment of a brake beam hanger bracket 19 which may be of conventional construction.

The spring plank is a one piece metal casting and is provided with a depressed portion 20 extending transversely across each of the spring seating portions 10. Each depressed portion 20 is provided with a concave downwardly facing bearing recess 21 that is formed to seat upon a pivot bar 8 and each depressed portion has a convex upper surface 22 below the level of the top face of the plank. The upper surface 22 of the depressed portion 20 has a central rib 23 extending the full length thereof and laterally spaced ribs 24 disposed at right angles to the rib 23. The ribs 23 and 24 have top edges flush with the top face of the spring seating portion 10 and form part of the spring seat, the depressed portion 20 being divided by the ribs 23 and 24 into a series of recesses 25. The ribs 23 and 24 stiffen the spring seating portions of the plank that would otherwise be weakened by the transverse depre-

sions, and, since the thickness of the ribs is substantially the same as the plank, the cooling of the spring seating portions of the casting is substantially uniform and the casting is not deformed or weakened by internal strains.

At the inner edges of the spring seating portions 10 midway between the side edges of the plank, integral upstanding spring positioning lugs 26 are provided and centrally of each spring seat upstanding positioning lugs 21 are formed integrally with the central rib 23. The lugs 26 and 27 cooperate with the rounded portions 15 and 16 of the flange 14 to position coil springs 11 on each seat 10, the lugs and flanges engaging the springs at circumferentially spaced points to hold the springs against lateral displacement on the seats. The seats are also preferably provided with hollow bosses 28 which are adapted to center the inner coils of double coil springs on the seats.

Safety loops 29 are preferably provided at each end of each of the bearing recesses 21, the loops 29 being formed integrally with the spring plank 9 and being of a width and depth to receive the pivot bars 8 and allow play between the pivot bars and spring plank. The loops 29 prevent the pivot bars 8 from becoming detached from the bearing recesses 21 and also serve to strengthen the ends of the spring plank, bracing webs 30 preferably being provided between the bottom of the spring plank and the opposite sides of each of the safety loops.

It is to be understood that variations and modifications of the specific devices herein shown and described for purposes of illustration, may be made without departing from the spirit of the invention.

What I claim is:

1. A one piece cast metal spring plank having an elongated body portion and widened end portions, the upper faces of which provide seats for coil spring groups, said plank having a marginal upwardly projecting flange extending along its sides and around its ends, the portions of the flange bordering the spring seats having rounded spring positioning portions, said body portion of the plank having laterally projecting stiffening and attachment flanges intermediate its ends, said end portions each having upwardly projecting centrally disposed spring positioning lugs.

2. A one piece cast metal spring plank having widened end portions, the upper faces of which provide seats for coil spring groups, said plank having a marginal upwardly projecting flange extending along its sides and around its ends, said flange having a series of rounded spring positioning portions engageable with the peripheries of coil springs mounted on said end portions, said end portions having integral upwardly projecting spring positioning lugs spaced inwardly from the spring positioning portions of said flange, each end portion having an integral bear-

ing portion extending transversely across the under side thereof, each bearing portion having a downwardly facing concave pivot receiving recess extending throughout the length thereof, the upper faces of said end portions having recesses overlying said bearing portions and integral stiffening ribs in said recesses.

3. A one piece cast metal spring plank having widened end portions, the upper faces of which provide seats for coil spring groups, said plank having a marginal upwardly projecting flange extending along its sides and around its ends, said flange having a series of rounded spring positioning portions engageable with the peripheries of coil springs mounted on said end portions, said end portions having integral upwardly projecting spring positioning lugs spaced inwardly from the spring positioning portions of said flange, each end portion having an integral bearing portion extending transversely across the under side thereof, each bearing portion having a transversely concave pivot receiving recess extending across the under side of an end portion of the plank, the upper faces of said end portions having recesses overlying said bearing portions and stiffening ribs in said recesses having upper edges flush with the upper faces of said end portions and forming portions of the spring seats.

4. A one piece cast metal spring plank having end portions having flat upper faces providing seats for coil spring groups, marginal flanges at the ends of the plank having portions of which are shaped to exteriorly engage coil springs of said groups, bearing portions having downwardly facing pivot recesses extending transversely across said end portions, the upper faces of said end portions having a depressed portion overlying said bearing portions, integral stiffening ribs in said depressed portion having upper edges flush with the upper face of the plank and forming portions of the spring seat, lugs integral with certain of said ribs and forming central spring positioning members, and an integral positioning lug disposed centrally of the plank adjacent the inner edge of each spring seat.
